(57) **CLAIM**

The ornamental design for [a rear panel of] an enclosure for
a peritoneal dialysis device, as shown and described.

DESCRIPTION

FIG. 1 is a back, bottom, and left side perspective view of
the [rear panel of an] enclosure for a peritoneal dialysis
device, showing the new design;

FIG. 2 is a back, bottom, and right side perspective view
thereof;

FIG. 3 is a back side elevational view thereof;

FIG. 4 is a bottom plan view thereof;

FIG. 5 is a top plan view thereof;

FIG. 6 is a left side elevational view thereof; and,

FIG. 7 is a right side elevational view thereof.

The broken lines [represent unclaimed] depict portions of
the [rear panel of an] enclosure [and form no] for a perito-
neal dialysis device in which the design is embodied that are
not considered part of the claimed design.
